US00D791144S

(12) **United States Design Patent** (10) **Patent No.:** **US D791,144 S**
Li et al. (45) **Date of Patent:** **** Jul. 4, 2017**

(54) **DISPLAY WITH GRAPHICAL USER INTERFACE**

(71) Applicant: **MITSUBISHI ELECTRIC CORPORATION**, Tokyo (JP)

(72) Inventors: **Haozhou Li**, Tokyo (JP); **Takaki Yagisawa**, Tokyo (JP); **Taro Kumagai**, Tokyo (JP)

(73) Assignee: **Mitsubishi Electric Corporation**, Tokyo (JP)

(**) Term: **14 Years**

(21) Appl. No.: **29/518,168**

(22) Filed: **Feb. 20, 2015**

(30) **Foreign Application Priority Data**

Aug. 21, 2014 (JP) 2014-018288
 Dec. 4, 2014 (JP) 2014-027119

OTHER PUBLICATIONS

An Office Action; "Notice of Reasons for Rejection," issued by the Japanese Patent Office on May 7, 2015, which corresponds to Japanese Design Patent Application No. 2014-018288 and is related to Design U.S. Appl. No. 29/518,168.

Primary Examiner — Kevin Rudzinski

(74) *Attorney, Agent, or Firm* — Studebaker & Brackett PC

(57) **CLAIM**

The ornamental design for a display with graphical user interface, as shown and described.

DESCRIPTION

The FIGURE is a front view of an image screen of a display with graphical user interface showing our new design. The broken lines shown represent the display and portions of the graphical user interface and form no part of the claimed design. The dash-dot lines represent the boundary between the claimed and unclaimed subject matter.

1 Claim, 1 Drawing Sheet
